VERTICALLY RECIPROCATING DOOR INSTALLATION AND OPERATING MEANS

Charles E. Schlytern, Detroit, Mich.

Application March 21, 1947, Serial No. 736,373

4 Claims. (Cl. 268—59)

1

My invention pertains to electrical motorized or power driven operating means and more especially to a system for operating a member, such as an upward acting door for example, which is to be moved back and forth at will and to various subcombinations of such a system, as well as elements, per se.

It is an object of my invention to provide an improved electric power operated system for moving a member, such as a door for example, back and forth between two extreme positions, which is especially convenient to install, operate and maintain, and which is reliable in operation.

It is a further object of my invention to provide such a motorized system which is especially advantageous for operating upward acting doors.

It is also an object of my invention to provide an improved compact electric operator pack of an electric motor and controls in a unit which is especially convenient to install and wire. This invention is claimed in my copending divisional application Serial No. 49,250 filed September 14, 1948.

Another object of my invention is to provide an improved cable and cable sheave combination which is advantageous for use in operator systems.

A further object of my invention is to provide an improved sheave.

Further objects and advantages are within the scope of my invention, such as relate to the arrangement, operation and function of the related elements of the structure, to various details of the construction and to combinations of parts, elements per se, and to economies of manufacture and numerous other features as will be apparent from a consideration of the specification in conjunction with the drawings disclosing specific embodiments of the invention, in which:

Fig. 1 is an elevational view showing the rear or inside of an upward acting door arranged for power operation in accordance with the invention;

Fig. 2 is a sectional view taken on line 2—2 of Fig. 1;

Fig. 3 is a side elevational view showing the power and control unit;

Fig. 4 is an elevational view showing the inner side or garage side of the power unit;

Fig. 5 is a bottom view of the power unit;

Fig. 6 is a plan view of the control supporting bracket;

Fig. 7 is a plan view of the socket plate;

Fig. 8 is a diagram for illustrating the operation of the reversing switch by the down limit stop on the door;

Fig. 9 is a diagram showing operation of the reversing switch by the up limit stop from the cable;

Fig. 10 is a schematic view representing the

2

door balancing and operating spring and cable system;

Fig. 11 is a side elevational view showing my improved cable sheave;

Fig. 12 is a cross-sectional view on line 12—12 of Fig. 11;

Fig. 13 is a diagrammatic view illustrating the operation of the special cable in such a sheave;

Fig. 14 is an enlarged fragmentary view showing the lock and the electromagnetically movable lock strike;

Fig. 15 is a cross-sectional view on line 15—15 in Fig. 14; and

Fig. 16 is a wiring diagram schematically representing the electrical circuits and control means for operating the motor, the electric light and the lock strike.

Referring more specifically to Figs. 1 and 2 I have illustratively disclosed a wall 11 having a doorway 13 closed by an overhead door 15, which may be of any conventional construction comprising a plurality of door sections 15' each extending horizontally across the doorway and hinged together in the usual vertical edge-to-edge relation. As usual in such installations, guide tracks 17 are provided extending on both sides of the doorway for receiving guides or rollers 19 extending from the edges of the door, to guide or change the direction of movement of the door in its up or down movements, and if there is not sufficient overhead space to receive the door in its uppermost or open position, it is common to curve the guide tracks in toward a horizontal position supported by hanger brackets 20 from the permanent building structure, as shown.

To provide well balanced easy operation of the door evenly at both sides, in accordance with my invention, a cross-shaft 21 is provided extending across over the doorway and rotatively supported in two bearing brackets 23 which may be mounted on the horizontal track braces 25, or on the building structure. The shaft carries two cable sheaves 27 secured firmly thereon, as by set screws 29 or by keys if preferred, and disposed adjacent the ends of the shaft and over the side edges of the door for passing cables 31 extending thereover and down to the bottom of the door where the ends of the cables are anchored by securing around holds 33 on the door. Fig. 10 also diagrammatically illustrates the cable arrangement.

From the cable sheaves 27 on the ends of the shaft the cables 31 pass through floating sheaves 35 and then return to have the other ends anchored in the horizontal track braces 25, or on the building structure. The two floating spring sheaves 35 are attached to one end of two counterbalance springs 37, the other ends of which are anchored into the track hangers 20, or to

any stationary object or structure. The counter-balancing springs 37 are suitably selected and so tensioned in installation that the weight of the door is practically supported by the springs in all positions. As the door moves either straight upward or turns up on the horizontal overhead portions of the tracks, as shown, the tension eases on the springs but as the door descends to closed position the tension of the springs increases and supports the door weight. 10

For operating the door, I provide a compact operator pack or power unit comprising a conventional geared electric motor M having a housing 41 on one end enclosing a speed reducing worm gear transmission, on which I provide a drive shaft 43 extending to both sides for convenient coupling, as by a loose coupler 44, to the door shaft 21 from either the right-hand or the left-hand side of the door. 15

As Figs. 3 and 4 show more clearly, on the opposite end of such a motor I install a second housing 45 which is secured by screws 47 to a bracket 49, of a generally U-shaped cross-section, and the upper ends of the side-walls of this bracket are secured to the adjacent end bell of the motor, as by screws 51. This bracket is seen in side elevation in Fig. 4 and edge or end elevation in Fig. 3. Fig. 6 shows a plan view of the bracket, where it is seen that the four outer corners of the side-walls are provided with holes 53 for receiving the motor attachment screws 51, and the lower yoke portion of the bracket is provided with holes 55 for the screws 47. In the center of the lower yoke of this bracket a hole 57 is provided for receiving the mounting bushing to mount a conventional panel type toggle switch 59 held in the bracket by the usual panel nut 50 with the toggle lever and terminal ball 50' projecting externally. Between the lower end or yoke of the bracket 49 and the lower end of the housing 41, a socket plate 61 is preferably provided. This socket plate 61 is seen in plan view in Fig. 7 and the edge may be seen in Figs. 3 and 4, and the dotted outline is shown in Fig. 5. This socket plate 61 and the end of the housing 41 are of course provided with holes 55' corresponding to the holes 55 in the bracket, as well as a central aperture 57' corresponding to the hole 57 for mounting the snap switch therein. Conventional electric sockets 63 are mounted in and through the end wall of the housing 41 in outwardly opening relation for receiving a fuse 65 and an electric incandescent lamp 67 to be connected into the control circuits, in a manner to be subsequently described. The socket plate 61 has suitable apertures 69 for passing the conventional electric sockets therethrough, the end wall of the housing is provided with similar apertures, and openings 71 are cut out of the sidewalls of the bracket to accommodate the sides of these sockets. Mounted upon one of the side-walls of the bracket 49 is an initiation or sequence relay R. The structure and operations of the switch and the relay will be subsequently described in detail, with reference to the wiring diagram Fig. 16. 55

A lock 73 is secured and carried on the rear or inner side of one of the door section panels 15' with its bolt 75 projecting to one side suitably to engage the inclined surface or cam 77 on a lock strike 79, as may be seen in Figs. 1, 2, 14 and 15. This arrangement is such that, as the door descends, the lock bolt 75 is depressed by the inclined cam surface 77 of the lock strike and then the lock bolt snaps out under the lock strike, 70 75

as shown in Figs. 1, 14 and 15, to hold the door locked down in a closed position. A key hole 79 (shown dotted) is provided through the door panel 15' and also the block 81 whereon the lock is mounted so that it can be conveniently controlled by an authorized person on the outside, and of course it may be controlled from the inside by the conventional knob 83. The lock 73 may be any conventional cylinder and latch type of lock. 10

So that the door may be automatically unlocked when the electric motor is energized to open the door, I support the lock strike 79 movably for control by a solenoid or electromagnet 85, which is connected by wires 86 to be energized when the motor is energized, as will be subsequently described. For this purpose, the lock strike 79 may be pivotally mounted on a pivot pin 87 which is supported in a stationary plate 89 secured to the wall or door casing, as by screws 91. The relation of the movable and the stationary parts of the lock strike are much like the two parts of a door hinge, except that a portion of the stationary plate 89 is bent away from the building structure to extend alongside the guide track 17, and the movable part 79 of the lock strike is bent to curve around the guide rail 17, as may be seen in Figs. 14 and 15, with a portion 93 projecting to the other side of the pivot pin to be attracted as an armature by the electromagnet 85, to swing the cam and lock strike surface 77 back to the unlocked position, shown by dotted lines in Fig. 15. A spring 95 is provided curled around the mid-portion of the pivot pin 87. One end of this spring reacts against the stationary part of the lock strike so that the other end of the spring normally biases the movable part of the lock strike to the locking position, shown in full lines in Fig. 15. 30 35 40

Figs. 11 and 12 show my improved sheave, for use in such systems, comprising a hub 97 of tubular stock and two side sheave members 99 which are centrally apertured for fitting upon the hub. The central portions of the sheave side members are flat and disc-like to fit snugly together in side-by-side relation, and the outer marginal portions are relatively dished or inclined. The sheave side members 99 are assembled on the hub with the dished margins diverging or spreading apart to provide an annular cable receiving groove opening outwardly around the sheave. The hub may be conveniently made of tubular stock and the sheave side members may be stamped out of sheet metal of suitable gauge. The sheave side members are conveniently secured to the hub, as by welding, and may also be secured together, as by spot welding between the flat central portions. The hub may be drilled and threaded for receiving the set screw or pin 29. 50 55 60 65

I have found that by utilizing in such a system and with such sheaves, a soft steel cable of the type having a cotton center, especially advantageous results are obtained. The frictional drive contact in the V-sheaves is dependent upon the soft steel cables deforming to bottom in the sheaves, as represented in Fig. 13, from the equal load implied by the door and the reacting force of the springs. Any unbalance of these normally equal loads would prevent the cable from bottoming in the sheaves thus providing slippage, which is an important safety factor. 70

Fig. 16 diagrammatically represents the connection of the electric motor M into a system with the service lines for energization and opera-

tion through the control devices previously described. The reversing switch 59 is a conventional 3-pole double throw switch having three blades tied together to move either to the right-hand side to operatively engage a corresponding set of three stationary contacts or to the left-hand side to engage another set of three stationary contacts. From the upper and the middle blades of the reversing switch 59, wires 101 and 103 respectively extend to the terminals of one of the windings M1 of the motor. The bottom blade of the reversing switch 59 is connected by a wire 105 to one terminal of the other winding M2 of the motor, and the other terminal of this winding is connected by a wire 107 to the upper right-hand stationary contact, and from whence a wire 109 connects to the center left-hand contact of this switch. From the bottom blade of the reversing switch, a wire connects to the upper left-hand and also to the central right-hand contacts, although this may be all accomplished by means of the single wire 105 extending from this blade to the motor. From the lower right-hand contact of the reversing switch a wire 111 connects to the right-hand stationary contact of the initiating relay R and a wire 113 connects from the left-hand stationary contact of this relay to the left-hand lower contact of the reversing switch.

The initiating or sequence relay R has a single movable blade 115 which is moved to engage first one and then the other one of its two stationary contacts by the successive energization or pulsing of a winding 117 in a manner common with such relays, as by means of the well known pawl and ratchet arrangement (not shown). This movable blade 115 is connected by a wire 119 to one end of the coil 117, where also is connected one end of the service line L2. From the other terminal of the relay winding 117 a wire 121 connects the one side of a push button 123 or any other suitable actuating means. The other line conductor L1 connects to one end of the fuse 65 (by connection to one side of the fuse socket) from the other end of which a wire 125 connects to the center left-hand stationary contact of the reversing switch 59. From the other end of fuse 65 and wire 125, a wire 127 connects to the other side of the push button 123. The lamp 67 is connected across the bottom and the center left-hand contacts of the reversing switch 59, and the connection of the motor windings into the system is so selected that when this reversing switch is in its left-hand position, the direction of operation is to open the door. The lock release electromagnet 85 is connected by wires 86 to the lower movable blade and to the left-hand center contact of the reversing switch. Hence the lamp 67 is lighted and the lock is released when the system is energized to "open" the door.

In operation: By operating the push button 123 a circuit is completed which energizes the winding 117 of the sequence relay R. This causes the relay R to throw its blade 115 to its opposite or alternate position in a well known manner. This completes the motor energizing circuits, the two windings M1 and M2 being energized to run the motor in a direction as predetermined by the set position of the reversing switch 59. As the door 15 approaches its extreme position the reversing switch 59 is thrown over thus interrupting the operation and setting the motor circuits for reverse operation the next time the relay R is operated by the push button 123.

This throw over of the reversing switch is ac-

complished by means of a lever 129 which is pivotally supported on one of the screws 47 on the bottom of the power unit. The inner end of this lever 129 is apertured and bent down suitably to receive the ball 50 on the lower end of the toggle lever of the reversing switch. The other end of this lever carries a roller 131 projected suitably from the power unit to be adjacent the door which carries a bracket 133 having an inclined cam 135 which strikes the roller and moves it outwardly toward the door. For clearness this operation is diagrammatically represented in Fig. 8. For the up limit operation, an up limit lever 137 is pivotally mounted on a stationary bracket 139 below the power unit and it extends up along the track 19 to the door side of the switch lever, which it engages by a projection 140. The upper end of this up limit lever 137 is bent and provided with a roller 141 which is suitably positioned to be pulled inwardly away from the door by the cable 31 as the door reaches its uppermost position. This operation is diagrammatically shown in Fig. 9.

In view of the power unit having controls compactly assembled it may be very conveniently installed and wired. The service conductors L1 and L2 may be the conductors of the plug in cord 143 shown in Fig. 1, and it is only necessary to plug in the energizing connection after the power unit has been mounted in proper relation to its limit controls. Usually it will be preferred to mount the push button 123, or other actuating means, separately from the unit, as for example on the wall of the garage as shown. Also a plurality of the actuating push buttons 123 may be provided and connected in parallel, as represented in Fig. 16. One such push button may be mounted inside of the house and perhaps it may be desired to mount one on a post adjacent the driveway, with a suitable locked cover (not shown). Also 123 symbolizes any other suitable actuating means such as a floor plate, electric eye, driveway coil magnetic pick-up, radio or other known control means. A base is fabricated of angle irons 145 and a plate 147.

Although an overhead type of door installation has been shown, it is to be understood that my improved operating means may be advantageously utilized with any upward acting doors, or even for other members which are to be moved between two extreme positions.

It is apparent that within the scope of my invention modifications and different arrangements may be made other than herein disclosed, and the present disclosure is illustrative merely, the invention comprehending variations thereof.

What is claimed as the invention is:

1. In an upward acting door and locking arrangement the combination of, a wall having a doorway to be closed, a door of suitable size and shape for closing said doorway, means movably supporting said door for movement either upwardly to open the doorway or downwardly to close the doorway, a lock mounted on the door adjacent one edge thereof, said lock having a horizontally projected lock bolt extendable beyond the edge of the door, a lock strike, means movably mounting said lock strike on a stationary structure adjacent the edge of the doorway to be engaged by said lock bolt as the door moves down to a closed position, said lock strike having an inclined surface positioned for engaging the end of the lock bolt and pushing it to retracted position in the lock as the door descends and then receiving the lock bolt projected under the

lock strike for locking the door down in its closed position, resilient means normally moving said lock strike to the lock bolt engaging position, manual unlocking means for said lock operative from the outer side of said door, and electromagnetic means for moving said lock strike to a disengaged position for unlocking the door so that the door can be raised.

2. An upward acting door and locking arrangement in accordance with claim 1 and further characterized by having a reversible electric motor, door operating means driven by said motor to move the door to opened or to closed position, and circuit means connecting said electromagnetic means to be energized to unlock the door when the motor is energized to open the door.

3. In a motorized upward acting door installation the combination of, a wall having a doorway to be closed, a door for closing said doorway, guide means adjacent the opposite edges of the doorway for guiding the door in its movements adjacent thereto, a shaft rotatively disposed over the doorway, two V-type cable sheaves supported and secured on said shaft respectively above opposite edges of the door, a pair of cables disposed to run individually over said cable sheaves with one end of each cable extending down and connected to the lower part of the door, said cables being of soft stranded steel having centers of fibrous non-metallic material, counterbalancing means connected with the portions of said cables running over said sheaves for tensioning the cable to engage in said sheaves and to counterbalance the weight of the door in its various positions, and a reversible electric motor connected with said shaft to move the door up and down as desired.

4. In a motorized upward acting door installation the combination of, a wall having a doorway to be closed, a sectional door for closing said doorway, two guide tracks disposed one adjacent each edge of the doorway in said wall, guide means extending from the edges of the door to cooperatively engage said guide tracks for guiding the door in its up and down movements, the upper portions of said guide tracks curving inwardly away from the wall so that the door moves to a substantially horizontal position above the doorway as it is raised to an open position, a pair of door balancing springs, means anchoring and holding one end of each spring at a position inwardly from the wall above the door-

5
10
15

way, a pair of floating cable sheaves one on the other end of each spring, a pair of cables one passing through each floating sheave, said cables being of soft stranded steel having centers of fibrous non-metallic material, a shaft rotatively supported extending across over the doorway, two cable sheaves having V-shaped cable grooves and secured upon said shaft one above each opposite edge of the door, said cables passing over the cable sheaves and down to connect with the lower portion of the corresponding edge of the door, the other end of each cable being anchored after passing through its floating sheave, said springs being selected of suitable strength and said springs and cables being of suitable lengths and suitably tensioned so that the main portion of the weight of the door is balanced by the springs as the door moves up or down adjacent the doorway or as it turns inwardly along the upper horizontal portions of said guide tracks, and reversible power means connected with said shaft for moving the door up or down to open or close said doorway as desired.
